UNITED STATES PATENT OFFICE.

ROBERT P. ASHBAUGH, OF RIVER FOREST, AND SAMUEL C. CAWTHON, OF CICERO, ILLINOIS, ASSIGNORS TO WESTERN ELECTRIC COMPANY, INCORPORATED, OF NEW YORK, N. Y., A CORPORATION OF NEW YORK.

WINDING MECHANISM.

1,376,914.

Specification of Letters Patent.

Patented May 3, 1921.

Original application filed March 25, 1919, Serial No. 285,000. Divided and this application filed July 10, 1920. Serial No. 395,298.

To all whom it may concern:

Be it known that we, ROBERT P. ASHBAUGH and SAMUEL C. CAWTHON, citizens of the United States, residing at River Forest, 5 in the county of Cook and State of Illinois, and Cicero, in the county of Cook and State of Illinois, respectively, have invented certain new and useful Improvements in Winding Mechanism, of which the following is a 10 full, clear, concise, and exact description.

This invention relates to winding mechanism, and more particularly to a winding head for applying insulating tape to conductors.

15 The object of this invention is to provide a simple and practical mechanism for applying a hemmed or lapped tape to a conductor in accordance with the features of the invention as disclosed in our co-pending application, Serial No. 285,000, filed March 25, 1919, of which this application is a division. Such a mechanism may comprise in general a winding head and a plurality of tape guides, one of which is provided with a curved slot therein by reason 20 of which the paper passing through it has one margin turned or lapped in such a manner that its application to the conductor will form a spiral ridge which positively 25 supports the rest of the tape out of contact with the conductor. The guides for the tape are made adjustable so that the angle of application of the tape to the conductor may be varied within reasonable limits. A 30 flexible cone guide and a polisher are also provided which serve to apply the tape to the conductor with a uniform cylindrical surface.

35 In the drawings illustrating this invention—

Figure 1 is an enlarged view of an insulated conductor made in accordance with this invention and showing the insulating tape unwound for a short distance;

40 Fig. 2 is an enlarged longitudinal sectional view illustrating the relation of the tape and conductor covered thereby;

Fig. 3 is an enlarged cross-sectional view taken upon line 3—3 of Fig. 1;

45 Fig. 4 is a view in front elevation of a winding head by means of which the insulation is applied to the conductor in the form shown in Figs. 1, 2, and 3;

Fig. 5 is a fragmentary detail view of the mechanism illustrated in Fig. 4; 55

Fig. 6 is a plan view of a guide forming a part of the winding mechanism, and

Fig. 7 is a plan view of a swing lever carrying the polisher.

Referring now to Figs. 1, 2, and 3, 5 represents a conductor around which is spiraled an insulating tape 6, preferably of paper, having on the lower margin thereof a ridge 7 which is formed by hemming or lapping one margin of the tape before it is applied 60 to the conductor. The tape covering 6 is supported by the ridge 7 and forms a smooth cylindrical shell of uniform external diameter about the conductor 5 which is centered within the tape covering 6 by means 65 of the ridge 7 and is substantially parallel to the tape covering. By means of the ridge 7, which is formed by hemming or lapping the margin of the tape, the body of the tape is positively maintained out of contact with the wire, due to the fact that with 70 such a ridge the pressure upon conductors so insulated is unlikely to cause a collapse of the insulation against the conductor, and the air space thus provided is maintained 75 even under conditions of pressure which result from the twisting of the conductors into pairs and cables.

In Fig. 4, 10 designates a winding head which may be driven in any suitable manner 85 and upon which is mounted a tape roll 11 in a manner to unwind in the direction of rotation of the head. Secured to said head is an upright wire guide member 12 through which a wire 13 to be insulated is drawn. 90 A guide member 14 mounted upon the upper end of the member 12 is provided with an opening about twice the size of the wire which is to be insulated, which opening permits of the passage of an enlarged portion 95 of the wire which may result from splicing. Pivotally and adjustably mounted upon the wire guide member 14 is an angle arm 16 which carries a guide member 17 having a curved or J-shaped slot 18 therein, through 100 which the tape 19 passes and is lapped or turned over at one margin thereof. As the tape leaves the guide member 17 it is wrapped about the wire 13 and is drawn through a flexible cone guide 20 and a polisher 105 21 which compress the tape 19 about the wire

and give to it a smooth cylindrical surface.

Mounted near the lower end of the wire guide member 12 is a second pivotal arm 22 upon which is adjustably mounted a pivotal guide lever 23 which serves to guide the tape from the supply roll 11 to the guide member 17 and to maintain the two edges thereof in parallelism and in the same plane.

10 Secured to the lower base of the pivotal arm 22 is a spring member 25 which rests upon the top of the tape roll 11 and acts as a brake thereon to prevent overrunning of the tape roll.

15 At its outer end the arm 22 is provided with a slot 26 through which extends a spring held catch member 27 supported in a post 28 secured to the head 10. The catch member 27 permits the release of the arm 22 so that it may be swung from a horizontal to a vertical position to permit a new tape roll to be supplied upon the head 10.

20 The flexible guide 20 and the polisher 21 are removably mounted in the end of a pivotal lever arm 30 which may be swung to one side to permit a new tape roll to slip over the guide 20, the polisher 21, the guide 17, the guide 14, the lever arm 22 and its associated parts, and into position upon the head 10 from which the tape may be fed onto the conductor.

25 The tape as it leaves the roll 11 is passed around a guide post 36 under the guide finger 23 and through the guide member 17 onto the wire.

30 The polisher 21 is held in position in the pivotal arm 30 by means of a clamping screw 38.

35 What is claimed is:

- 40 1. A combined forming and winding head for applying a lapped or hemmed paper tape to a conductor, comprising a rotating supporting table for the tape, a wire guide through which the wire to be covered is drawn, and a tape guide carried by said wire guide for lapping one margin of the tape before the tape is wound upon the conductor.
- 45 2. In a head for insulating conductors with tape, a tape supply roll, a rotatable support for said tape supply roll, a wire

guide carried by said rotatable support through which the wire to be covered is drawn, and a tape guide and former carried by said wire guide for lapping one margin 55 of said tape and guiding it onto the wire.

3. In a winding head for insulating conductors with tape, a tape supply roll, a rotatable support therefor, a wire guide carried by said support through which the wire 60 to be covered is drawn, a tape guide having a curved slot therein for bending over one edge of said tape, and a conical guide member and a polisher surrounding said wire above said guide for forming said tape into 65 a tube around the wire.

4. In a winding head for insulating conductors with tape, a tape supply roll, a rotatable support therefor, a wire guide carried by said support through which the 70 wire to be covered is drawn, a tape guide having a J-shaped slot therein for turning over one edge of the tape, and a flexible conical member and a polisher surrounding said wire above said guide for forming said 75 turned-over tape into a smooth surfaced cylinder around said wire.

5. In a winding head for insulating conductors with tape, a tape supply roll, a rotatable support therefor, a wire guide carried by said support through which the wire 80 to be covered is drawn, and a pair of adjustably mounted tape guides carried by said wire guide, one of said guides being provided with means for lapping or hemming one margin of the tape.

6. In a winding head for insulating conductors with tape, a tape supply roll, a rotatable support therefor, a wire guide carried by said support through which the wire 90 to be covered is drawn, an adjustable guide carried by said wire guide at one end thereof and having a curved slot therein for lapping one edge of said tape as it passes therethrough, and a second adjustable guide located at the opposite end of said wire guide for leading the tape to the slot in the slotted guide.

In witness whereof, we hereunto subscribe our names this 23 day of June, A. D. 1920.

ROBERT P. ASHBAUGH.
SAMUEL C. CAWTHON.
